UNITED STATES PATENT OFFICE.

JULES E. SCHNEIDER, OF DALLAS, TEXAS, ASSIGNOR TO BEACH-WAGSTAFF RUBBER CORPORATION, OF DALLAS, TEXAS.

DESIGN FOR A RUBBER-TIRE TREAD.

58,113.

Specification for Design.

Patented June 7, 1921.

Application filed February 10, 1920. Serial No. 357,686. Term of patent 3½ years.

To all whom it may concern:

Be it known that I, JULES E. SCHNEIDER, a citizen of the United States, residing at Dallas, in the county of Dallas and State of Texas, have invented a new, original, and ornamental Design for Rubber-Tire Treads, of which the following is a specification, reference being made to the accompanying drawing, forming part thereof.

Figure 1, is a face view of the tire showing my design, and

Fig. 2, is a cross-sectional view through the tire, taken on line 2—2 of Fig. 1.

I claim:

The ornamental design for a rubber tire tread as shown.

JULES E. SCHNEIDER.
